UNITED STATES PATENT OFFICE.

DARIUS S. TYLER AND LAMBERT D. TYLER, OF INDIANAPOLIS, INDIANA.

WASHING-MACHINE.

SPECIFICATION forming part of Letters Patent No. 727,497, dated May 5, 1903.

Application filed February 18, 1902. Serial No. 94,595. (No model.)

To all whom it may concern:

Be it known that we, DARIUS S. TYLER and LAMBERT D. TYLER, citizens of the United States, residing at Indianapolis, in the county 5 of Marion and State of Indiana, have made certain new and useful Improvements in Washing-Machines, of which the following is a specification.

Our invention is an improvement in washing-machines, and has for an object to provide a novel construction and combination of parts whereby to thoroughly and easily cleanse the clothing and to provide for turning the clothing during the washing operation, 10 as well as means for securing the wringer so the same can be quickly turned into and out of position for use; and the invention consists in certain novel constructions and combinations of parts, as will be hereinafter described and claimed.

In the drawings, Figure 1 is a perspective view, and Fig. 2 a longitudinal section, of a machine embodying our invention. Fig. 3 is a cross-section of the machine. Fig. 4 is a 15 detail view of the turning frame. Fig. 5 is a detail perspective view of one of the boxings to fit on the wrists of the cranks. Fig. 6 is a detail perspective view of one of the pounder-heads, and Fig. 7 is a detail view of the 20 wringer-bar.

In carrying out our invention we provide a body A in the form of a suds-box having a rounded bottom A' and preferably including a wooden box or casing and a lining of sheet metal, so the warping of the casing will not cause any leakage of the suds-box, the casing having its bottom A' curved so the turning frame can readily operate alongside the same in operation, as will be best understood from 25 Fig. 3. The turning frame B is a rectangular open frame having side bars B' and end bars B², the latter being pivoted at b² to the ends of the suds-box and one of the pivots b² being preferably extended, as shown in Figs. 1 and 30 2, and provided with a crank-handle b', as shown in said figures. This extension and crank-handle may be preferred, because thereby the frame can be readily turned without opening the lid of the box A. It will be 35 understood, however, that the frame B may be readily operated from within the box by

means of a suitable bar or rod or when the water is not too hot by the hand of the operator, the purpose of the frame B being to readily turn the clothing in the suds-box when it is 55 desired to expose fresh portions or surfaces to the action of the pounders, and said frame from its peculiar construction and arrangement, fitting as it does within the suds-box, serves such purpose in an efficient manner 60 and may be entirely revolved or only partially turned, as desired in securing the turning of the clothing. As shown in Fig. 4, the frame B has corner brace-plates B³, which strengthen it and prevent the clothing from getting in 65 the angles at the corners. The box A has a lid C, which is slotted at C' for the play of the pounders, and upon the lid are mounted brackets D, provided at D' with bearings for the drive-shaft E. This drive-shaft is 70 provided with the oppositely-projecting cranks E', whose wrists are connected with the pounders, and the said shaft is provided at one end with the wheel F, preferably formed by extending the rod from which the shaft E is 75 formed radially at E², then circularly to form the wheel-rim E³, and then at its ends to provide the crank-handle E⁴, by which the wheel and shaft may be turned in operating the machine. Upon the cranks E' we journal the 80 boxings G, which are preferably constructed, as shown in Fig. 5, with a center block H, which may be of wood, Babbitt metal, or other suitable material, and the strap I, which encircles the block H and has its ends 85 lapped together and secured by rivets or otherwise, as shown at I' in Figs. 3 and 5. This boxing G has an opening g for the wrists of the crank E', an opening g' for the pounder-rod, and an opening g² for the set-screw J, 90 which secures the pounder-rod in any desired adjustment. We also provide the boxing G with a depending rod G', which connects it with the cuff K on the swinging end of the swinging guide-rods K' for the pounder-rod, 95 the swinging guide-rods K' being provided one for each of the pounders and being pivoted at K² within the box A and carrying the cuffs K at their swinging ends, such cuffs being pivoted at k, as shown, and being connected by the rods G' with their respective boxings G, as shown. The cuff K is provided 100

with a set-screw k' , which operates to secure the pounder-rod L, so the said rod will be secured near its upper end by the screw J and near its lower end by the screw k' . Thus if either screw should become loosened the pounder-rod will be held by the other, and both screws can be loosened whenever it is desired to adjust the pounder-rod up or down, according to the bulk of clothing to be washed or for any other purpose desired. The pounder-rods L support the pounder-heads L' at their lower ends, the heads operating upon the clothing and serving by suction and compression to not only mechanically pound the clothing, but aid in cleaning the same by forcing the water to circulate through the clothes as may be desired.

The pounders are carried by the lid C and the swinging guide-rods K', and the lid C is hinged at C², so it can be turned from the closed position shown in full lines, Fig. 3, to the open position indicated in dotted lines in the said figure. In the dotted-line adjustment the swinging guide-rods K' turn up and stand against the rear side of the suds-box A and operate to secure the lid and pounder in the dotted-line position shown in Fig. 3.

It will be noticed that the turning frame B may be rocked when the pounders are within the suds-box and can be turned entirely over when the pounders are adjusted to the dotted-line position shown in Fig. 3. On one end of the box we secure a cleat M', arranged below the upper edge of the box and provided with a pivoted button M⁴, which may be turned into line with the cleat M' or to the upright position indicated in full lines, Fig. 2, to secure the wringer-supporting bar M when the latter is adjusted to a vertical position. The bar M is pivoted at its ends at N', so it can be turned vertically to support the wringer in operative position, as will be understood from Fig. 2, or horizontally, as shown in Fig. 1, when it is desired to throw the wringer out of the way when it is not in

use. When the wringer is turned to operative position, the button M⁴ secures it firmly in such position, so it can be readily operated.

Having thus described our invention, what we claim as new, and desire to secure by Letters Patent, is—

1. The machine herein described, comprising the suds-box having a curved bottom, the turning frame pivoted at its ends within said suds-box and open at its center for the operation of the pounders and arranged to be oscillated within the suds-box when the pounders are in operative position, the lid provided with bearings for the operating-shaft, the operating-shaft having cranks, the boxings secured to said cranks and having guide-openings for the pounder-rods and clamps for securing the pounder-rods in different adjustments, the swinging guide-rods pivoted at one end within the suds-box and provided at their swinging ends with means for clamping said pounder-rods, connections between said clamping means and the boxing on the cranks of the operating-shafts, and the pounders, and their rods secured in the boxing and the clamping means, and movable with the lid to a position where they will not interfere with the revolution of the turning frame, substantially as and for the purpose set forth.

2. The combination of the suds-box, the operating-shaft having cranks, the boxings secured on said cranks and composed of blocks and straps inclosing the said blocks, said boxings being provided with openings for the wrists of the cranks and for the pounder-rods, and the clamping-screws, the swinging guide-rods pivoted at one end to the suds-box and connected at their swinging ends with the pounder-rods, the pounder-rods and the pounders, substantially as set forth.

DARIUS S. TYLER.
LAMBERT D. TYLER.
